UNITED STATES PATENT OFFICE

155,961

DESIGN FOR A WEIGHING SCALE

Howard T. Ailor, Great Neck, N. Y.

Application April 5, 1948, Serial No. 145,540

Term of patent 14 years

(Cl. D52—10)

To all whom it may concern:

Be it known that I, Howard T. Ailor, a citizen of the United States, residing at Great Neck, in the county of Nassau, State of New York, have invented a new, original, and ornamental Design for a Weighing Scale, of which the following is a specification, reference being had to the accompanying drawing, forming part thereof.

Figure I is a perspective view of a weighing scale, showing my new design;

Figure II is a top plan view; and

Figure III is a side elevational view.

The rear of the scale housing is ornamented exactly the same as the front and sides thereof.

I claim:

The ornamental design for a weighing scale, as shown and described.

HOWARD T. AILOR.
